CLAIM

The ornamental design for a packaging container as shown and described.

DESCRIPTION

FIG. 1 is a front perspective view of a first embodiment of a packaging container showing our new design;
FIG. 2 is a rear perspective view thereof;
FIG. 3 is a top view thereof;
FIG. 4 is a front perspective view of a second embodiment of the packaging container showing our new design;
FIG. 5 is a rear perspective view thereof;
FIG. 6 is a top view thereof;
FIG. 7 is a front perspective view of a third embodiment of the packaging container showing our new design;
FIG. 8 is a rear perspective view thereof;
FIG. 9 is a top view thereof;
FIG. 10 is a front perspective view of a fourth embodiment of the packaging container showing our new design;
FIG. 11 is a rear perspective view thereof;
FIG. 12 is a top view thereof;
FIG. 13 is a front perspective view of a fifth embodiment of the packaging container showing our new design;
FIG. 14 is a rear perspective view thereof; and,
FIG. 15 is a top view thereof.
The broken lines in the drawings depict portions of the packaging container that form no part of the claimed design.
